TRAFFIC SIGNAL

Erwin Sibley, Milledgeville, Ga.

Application April 26, 1933, Serial No. 668,130

4 Claims. (CL 177—329)

This invention relates to a signal for controlling movements of vehicular traffic. More particularly, it relates to a signal adapted to be placed at a traffic intersection to control, in an orderly manner, all movements of traffic which are permitted by local laws.

The traffic regulations in many jurisdictions permit a vehicle approaching an intersection controlled by a traffic light or a traffic policeman to turn right while the traffic on the intersecting highway is moving, although, of course, such a vehicle may not proceed straight through the moving line of traffic or make a left turn. Since traffic rules are not uniform, however, and because in some jurisdictions a right turn on a red or stop signal is not permitted, it has been found desirable, in places where such right turn is permitted, to apprise the motorists of that fact, and to this end, separate signal lights, in the form of green right turn arrows, have been mounted adjacent the conventional red, amber, and green traffic lights. Such an addition of an extra traffic light is expensive, however, and is accompanied by complications in wiring and operation.

It is a primary object of the invention to produce an improved form of traffic signal having a face provided with signal areas shaped and illuminated to indicate the various movements of traffic permitted by the laws of a particular jurisdiction. It is a further object of the invention to greatly simplify the illumination of the various signal areas, and this is accomplished by constructing and arranging certain of the signal areas so that they will be brightly illuminated by reflected light to show predetermined signal colors constantly.

In one form of the invention, one signal is illuminated by transmitted light to show successively red and green colors to stop and to permit movement of traffic respectively, and this area preferably is shaped to indicate the direction of movement so permitted. In combination with the transmissively illuminated signal area, an additional signal area is used, and the latter is illuminated by reflected light to show a constant green signal, to indicate that a right turn may be made irrespective of the color of the transmissively illuminated, changeable area. I preferably associate with the reflectively illuminated signal, an additional signal area which may be constantly illuminated either red or amber by reflected light to indicate that a momentary stop must be made before traffic proceeds in accordance with the first mentioned reflectively illuminated area.

In a second form of the invention, I combine with the reflectively illuminated right turn arrow, an additional signal area which is illuminated by transmitted lights of different colors

to show red and green signals respectively. When this additional area is red, it indicates that a momentary stop must be made before traffic proceeds to turn right, in accordance with the suggestion of the green right turn arrow. However, when that area is green, the traffic may proceed to turn right without the necessity of a momentary stop. Preferably, this transmissively illuminated area, associated and combined with the reflectively illuminated area, changes color simultaneously with the principal transmissively illuminated signal area which controls straight ahead and left turn traffic. Thus, when through traffic is forbidden by a red signal appearing in the principal area, a right turn will be permitted by the reflectively illuminated green arrow, but only after a momentary stop has been made, in accordance with the transmissively illuminated red signal area associated therewith.

In another form of the invention, each signal area is illuminated by reflected light only. In this form, one area is made of a shape to indicate the direction of travel which the traffic may take after it has passed the signal, and this area is of a color to indicate permission to proceed in that direction. The other signal area is of a shape and color to indicate that a momentary stop must be made prior to proceeding in accordance with the instruction of the first mentioned area. A signal of this type will be found to be useful at the intersection of a side road with a main highway, and will supplant the conventional octagonal stop signs now in use.

In the accompanying drawing, I have shown a specific embodiment of each of the forms of the invention discussed above, but it will be understood that many variations in constructional details may be made without exceeding the scope of the invention.

In the drawing:—

Figure 1 is an elevational view of a traffic signal embodying the invention.

Figure 2 is a vertical sectional view on line 2—2 of Figure 4 in which the casing sides are perpendicular instead of inclined, and shows a suitable illuminating means.

Figure 3 is a horizontal sectional view of Figure 1 or 2.

Figure 4 is a modified form of the invention in which the signal area associated with the right turn signal is illuminated transmissively.

Figure 5 shows another arrangement of signal areas.

Figure 6 is an elevational view of a stop sign made in accordance with this invention.

In Figures 1 to 5, I show a traffic signal comprising a casing 10 having four slightly inclined signal faces 11, 11¹, 11², 11³, which are each pro-

vided with a plurality of signal areas, to control traffic approaching an intersection from four directions. Obviously, more or less faces would be provided for more or less roads leading to the intersection. If desired, a visor or shield may be associated with each signal face to protect the same from the weather, but care should be taken not to cast a heavy shadow upon the reflectively illuminated signal area, for if this is done, that area will not be illuminated sufficiently by daylight. Within the housing a single source of illumination, in the form of an electric light bulb 12, is provided. A cylindrical screen 13 is mounted for intermittent rotation about the bulb 12. The screen is provided with diametrically opposed green sections 14 and red sections 15. Thus, beams of red light are transmitted to the faces 11, 11¹, and beams of green light to the faces 11², 11³ (Fig. 3). When the cylindrical screen is rotated through 90°, the opposite will be the case and the faces formerly receiving red light will receive a green light and vice versa.

Referring to Figure 2, an electric motor 16 is indicated diagrammatically, and the same is preferably connected through an appropriate mechanism 17 to the post 19, which supports the screen. The mechanism 17 functions to impart to the post 19 a quick 90° turn at predetermined intervals. Many such devices are known in the art and since the particular construction thereof forms no part of the present invention, it will not be described further.

The interior of the casing is divided into four compartments by partition members 20, 21, so that light from one section of the screen can be projected only to one signal face at a certain time.

The construction and arrangement of the signal areas on the several faces of the housing is the most important part of the present invention. Referring to Figure 1, a plurality of transparent lenses 22 are assembled and supported in appropriate openings in the face 11 in the form of a straight ahead arrow 23 and a left turn arrow 24. Beneath this signal area, additional lenses may be assembled in the form of a horizontal bar 25. These lenses are adapted to be illuminated successively by red and green beams of light to show respectively red and green signals. Thus, when the lenses pass a red light, traffic which desires to proceed straight ahead or to turn left will be instructed to stop, whereas such traffic will be instructed to proceed when the lenses show a green light.

In combination with the transmissively illuminated signal area, I provide a right turn arrow 26 which is illuminated by reflected light from an external source, such as daylight, or headlight beams from approaching vehicles. The sections 27 may have any desired construction, and since reflectively illuminated traffic markers are known, any efficient means for showing a bright reflected light may be used. It is important that such reflected light be of a green color, and to this end either a green reflecting surface may be placed behind clear glass, or green glass may be used.

Associated with the reflectively illuminated right turn arrow is another signal area, which, in Figure 1, is indicated as a reflectively illuminated red bar 28. The red signal of this bar will indicate to traffic that a momentary stop is required before the traffic may proceed in accordance with the green right turn arrow.

The form of device disclosed in Figure 4 differs from that of Figure 1 only in that the signal area 28', associated with the reflectively illuminated right turn arrow 26, is adapted to be illuminated by transmitted light, in exactly the same manner as the straight ahead and left turn arrows 23, 24. Consequently, the bar 28' will indicate that right turn traffic must stop momentarily before proceeding, if the signals 23, 24 are red and cross-traffic is flowing. However, when signals 23, 24 are green and cross-traffic is not flowing, a right turn may be made in accordance with the indication of right turn arrow 26 without the necessity of a momentary stop, because the signal area 28' associated therewith will be green.

In Figure 5, the left turn and the straight ahead arrows are indicated as separate signal areas 23', 24'. Each may be illuminated by transmitted light, in accordance with the disclosure of Figures 1 to 4, and the right turn arrow 26 again should be illuminated reflectively. The bars beneath the arrows may be illuminated in either of the ways described above.

In Figure 6, a somewhat different form of the invention is disclosed. This comprises a signal or sign having a face 30, which is adapted to be positioned to receive light from passing vehicles. Upon the face, there are positioned two signal areas 31, 32, each of which is constructed and arranged to be illuminated by reflected light to show predetermined respectively different colors. As indicated, the signal area 31 will show a green light by reflection and the area 32 a red light. The area 31 is formed of a shape to indicate the direction which traffic may follow after passing the sign. Thus, if the sign is placed at the intersection of a side road with a main highway, the area 31 will be in the form shown in Figure 6, and will comprise a right turn arrow 33 and a left turn arrow 34. Of course, if the side road continues across and beyond the main highway, a straight ahead arrow would appear extending upwardly from the juncture of the shafts of the right and left turn arrows.

The signal area 32 is shaped and colored to indicate the necessity for a momentary stop. As disclosed, it is in the form of a horizontal bar and is colored red, because such a form is in the nature of a barrier and will instruct a driver to stop.

I claim:

1. In a traffic signal, a green signal, a red signal, and means to display said signals alternately and cyclically, a permanently displayed turn indicator, a bar under the turn indicator, and means to display said bar in colors corresponding to the traffic signal displayed, whereby a momentary stop is indicated with a turn on the red signal and permission to proceed without a momentary stop is indicated with a turn on the green signal.

2. In a traffic signal, a green signal, a red signal, and means to display said signals alternately and cyclically, a permanently displayed green turn indicator, a bar under the turn indicator, and means to display said bar in colors corresponding to the traffic signal displayed, whereby a momentary stop is indicated with a turn on the red signal and permission to proceed without a momentary stop is indicated with a turn on the green signal.

3. In a traffic signal, a housing having a wall, a translucent lens in the wall, and means within

said housing to transmit alternately and cyclically, red and green light through said lens, a permanently displayed turn indicator, a bar under the turn indicator, and means to display said bar in colors corresponding to the color of the lens, whereby a momentary stop is indicated with a turn on the red signal and permission to proceed without a preliminary stop is indicated on the green signal.

10 4. In a traffic signal, a housing having walls,

a translucent lens in one of said walls, and a permanently displayed turn indicator, a translucent bar under the turn indicator, and means within the housing to transmit alternately and cyclically, red and green light to illuminate said lens and said bar similarly, whereby a momentary stop is indicated with a turn on the red signal and permission to proceed without a preliminary stop is indicated on the green signal.
